UNITED STATES PATENT OFFICE.

JOSEPH A. DEDOUCH, OF OAK PARK, ILLINOIS.

MEDALLION MOUNTING.

Application filed May 4, 1925. Serial No. 28,038.

To all whom it may concern:

Be it known that I, JOSEPH A. DEDOUCH, a citizen of the United States, residing at Oak Park, in the county of Cook and State 5 of Illinois, have invented a new and useful Improvement in Medallion Mountings, of which the following is a specification.

This invention relates to mountings for medallions and the like and in particular 10 to medallions having a porcelain or earthenware body which are particularly adapted to be secured to the faces of tombstones and the like.

The invention is fully described in the 15 following specification and shown in the accompanying drawings in which:

Figure 1 is a front elevation of a medallion embodying the invention;

Fig. 2 is a rear elevation of the same;

20 Fig. 3 is a vertical section on the line 3 of Fig. 2;

Fig. 4 is a horizontal section on the line 4 of Fig. 3;

25 Fig. 5 is a perspective view of the clip for securing it to the face of the tombstone;

Fig. 6 is a rear elevation of a modified form of the device;

Fig. 7 is a vertical section on the line 7 of Fig. 6;

30 Fig. 8 is a perspective view of the clip shown in Fig. 6;

Fig. 9 is a rear elevation of a further modification of the device;

Fig. 10 is a vertical section on the line 10 of Fig. 9;

35 Figs. 11 and 12 are perspective views of the clip and cross bar respectively shown in Fig. 9;

Fig. 13 is a rear elevation of a further 40 modification of the device; and

Figs. 14 and 15 are vertical and horizontal sections on the lines 14 and 15 respectively of Fig. 15.

The embodiment shown in Fig. 1 comprises a medallion 16 upon the convexly curved outer face of which may be formed a picture, emblem or the like. The rear surface of the body 16 is preferably flat with a horizontally disposed depression 17 therein. Overhanging lips 18 overlie this depression near its center.

45 A clip 19 having straight sides is adapted to snap into this depression and beneath the lips 18. Inwardly facing spring fingers 20 and 21 are formed from the middle of the clip 19 and project therefrom on the

same side of the clip so that as the clip is forced under the lips 18 these fingers will engage the bottom of the depression 17.

Shoulders 22 and 23 are formed in the 60 bottom of the depression and are adapted to be engaged by the ends of the spring fingers 20 and 21, so that as the clip is forced inwardly the spring finger 21 will carry over the edge of the shoulder 23 and 65 snap behind it so that the clip can not be withdrawn. The upper end of the clip 24 is offset so as to lie substantially flat on the surface 25 to which it is adapted to be secured as by means of an expander bolt 26, 70 of any well known type, passing through the opening 27, the bolt 26 being secured to the base 25.

To prevent the clip 19 from turning about the bolt 26, an extension 24^a projects from 75 a convenient point as from the end 24 and into the surface 25. This also enables the clip to be held in a horizontal position when it is desirable to place the medallion with its long axis horizontal.

Thus to secure the medallion to the surface 25, the clip 19 is secured thereto by means of the expander bolt 26. The medallion 16 is then pushed up over the clip 19 until the spring finger 21 snaps over the 80 shoulder 23 when it can no longer be removed. The bolt 26 is preferably placed at the top as illustrated, so that the weight of the medallion hangs therefrom.

In Figs. 6 to 8 is shown a modification 85 of the device in which a spring clip 27 has two ears 28 which project from the sides and which are adapted to slide up over inclined shoulders 29 which terminate in shoulders 30. The clip 27 is secured to the face of a wall as previously described, by means of an expander bolt 26 after which the medallion 31 is placed over it and the medallion forced up until the ears 28 snap down behind the shoulders 30, thereby locking the 90 medallion onto the clip. As in the embodiment previously shown and described the clip and its attaching screw 26 being covered by the medallion, the whole is similarly secured to the surface of the tombstone and can not be removed without damage thereto.

95 Figs. 9 to 12 show a still further modification of the device in which a metal bar 32 is secured in the rear part of the medallion 110 and extends transversely across the vertical depression 34. In this case the clip 35 which

- is secured to the face of the tombstone as shown in Fig. 3 is a long body 36 which extends longitudinally through the slot 34 and over the back of the transverse bar 32. It has a spring finger 37 which passes over the bar and snaps behind it so as to prevent the removal of the clip therefrom. Stops 38 on the clip 35 limit the distance to which it can be forced in, while the sides of the clip engaging the sides of the depression 34 prevent the medallion from being moved laterally with respect to the clip. This is also true of the form shown in Fig. 6.

Figs. 13, 14 and 15 show another modification of the device in which the medallion 39 has a large depression 40 in its rear surface with a centrally disposed post rising therefrom. This has laterally extending lips 42 terminating in shoulders 43. The spring metal clip 44 is secured as previously described, to the surface to which it is desired to fasten the medallion and this is bifurcated to provide spring fingers 45 which pass on opposite sides of the post 41 and over the lips 42.

The fingers 45 are bent outwardly at 46 to provide shoulders which will snap over the shoulders 43. These are then terminated in beveled portions 47.

To apply this device to a tombstone or the like, a clip 44 is secured thereto as by means of an expander bolt as shown in Fig. 3. The medallion 39 is then pressed upwardly forcing the inclined ends 47 over the lips 42 until the shoulders 46 snap behind the shoulders 43 thereby retaining the clip on the back of the medallion. The slot between the fingers 45 is only slightly larger than the post 41 and of such a depth as to just permit the shoulders 46 to snap over the shoulders 43.

While I have shown and described but a few embodiments of this invention, it is to be understood that it is capable of many modifications. Changes therefore in the construction and arrangement may be made which do not depart from the spirit and scope of the invention as disclosed in the appended claims.

I claim:

1. In combination, a medallion having a depression in the rear face, a clip adapted to be secured to a surface to which it is desired to fasten said medallion, a groove hav-

ing integral lips on said rear face extending vertically along the back of the medallion, 55 and a transverse shoulder on said medallion for engaging a portion of said clip to retain the medallion thereon.

2. In combination, a medallion having a depression in the rear face, a clip adapted to 60 be secured to a surface to which it is desired to fasten said medallion, a groove having integral lips on said rear face extending vertically along the back of the medallion adapted to overlie said clip, and to engage the sides of said clip, a spring finger on said clip, and a transversely disposed shoulder adapted to be engaged by said spring finger to prevent withdrawal of the clip.

3. In combination, a medallion having a depression in the rear face, a clip adapted to 65 be secured to a surface to which it is desired to fasten said medallion, a groove having integral lips on said rear face extending vertically along the back of the medallion adapted to overlie said clip and to engage the sides of said clip, a plurality of spring fingers on said clip, and transversely disposed shoulders adapted to be engaged by 70 said spring fingers to prevent withdrawal of the clip.

4. In combination, a medallion having a depression in the rear face, a clip adapted to 75 be secured to a surface to which it is desired to fasten said medallion, a groove having integral lips on said rear face extending vertically along the back of the medallion adapted to overlie said clip and to engage the sides of said clip, two oppositely disposed fingers on said clip, and transversely disposed shoulders adapted to be engaged by 80 said spring fingers to prevent withdrawal of the clip.

5. In combination, a medallion having a depression in the rear face, a clip adapted to 85 be secured to a surface to which it is desired to fasten said medallion, said depression engaging the two sides of said clip to prevent lateral displacement of one with 90 respect to the other, a shoulder on said rear face, and a part of said clip adapted to spring into engagement with said shoulder to prevent withdrawal of said medallion from said clip.

JOSEPH A. DEDOUCH.
